DRAFTING DEVICE

Howard C. Blinsinger, Lansdowne, Pa.

Application October 18, 1937, Serial No. 169,674

5 Claims. (Cl. 101—301)

The object of the invention is to provide improvements in drafting devices broadly, but more especially in a type which has been designed and is particularly adapted for use in making layouts 5 of floor and wall plans for the arrangement of furniture, furnishings, machine and general equipment units, and in fact for all purposes to which the device is adaptable.

In the following specification, it is to be understood that while the description relates more or less specifically to kitchen layouts, involving the many possible arrangements of units designed for kitchen use, such description and the figures in the accompanying drawings are intended only to illustrate one of the many uses to which the improved drafting devices may be put.

More specifically, another object is to provide in such a device a compact carrying case in which the improved drafting board or base, the 20 series of novel stamps, the highly efficient supporting and positioning mechanism for said stamps, the ink pad, etc., can be transported from place to place, but which is at all times ready for immediate use.

25 A further object is to provide an improved design and construction of the individual stamps by which various units are indicated or represented, together with interchangeable means for readily adapting the device to unit stamps of 30 different sizes or widths, as well as means for accurately positioning the rubber or similar portions of such stamps upon their respective supporting elements.

With these and other objects in view, the invention comprises further details of construction and operation, which are hereinafter fully brought out in the following description, when read in conjunction with the accompanying drawings, in which Fig. 1 is a top plan view of a 35 drafting board or base, together with parts and accessories which combine to form one embodiment of the invention; Fig. 2 is a bottom plan view of the stamp-holding element; Fig. 3 is a side elevation of the same; Fig. 4 is a fragmentary side elevation of one of the replaceable stamp-positioning bars, together with the supporting means for its opposite ends; Fig. 5 is a section of the same on the line 5—5 of Fig. 4; Fig. 5a is an end elevation of the parts shown in 40 Figs. 2 and 3; Fig. 6 is a top plan view of one of the stamp supporting plates; Fig. 7 is a bottom plan view of the same with a stamp member affixed thereto; Fig. 8 is a top plan view of the 45 jig for properly positioning a stamp with respect to its supporting plate when being secured

thereto; Fig. 9 is a side elevation of the same with a fragmentary portion of a stamp and plate operatively positioned thereupon; Fig. 10 is an end elevation of the same; Fig. 11 is a section on the line 11—11 of Fig. 9; Fig. 12 represents an impression of one of the stamp members, as for instance, upon a sheet of layout paper; Fig. 13 represents a series of such impressions to jointly represent a side of a kitchen or similar room; Fig. 14 represents the consecutive impressions of 10 a series of stamp members, to indicate a plan of the available working surface provided by the first six units of the layout shown in Fig. 12; Fig. 15 is a plan view of a modification, comprising a combination of the functions of the guide 15 rod and the gauge or space bar shown in Figs. 1 to 5; Fig. 16 is an enlarged fragmentary sectional view on the line 16—16 of Fig. 15; Fig. 17 is a similar section but showing the relatively movable guide rod and radial arm in an intermediate position between two operating positions; Fig. 18 is a side elevation of the radial arm and a modified form of stamp supporting plate partly in section; and Fig. 19 is a bottom plan view of the modified form of plate and 25 attached stamp.

Referring to the drawings, the drafting board or base 1 may be surrounded by a shallow ledge 2 and, if desired, may also be provided with a cover (not shown), adapted to span, enclose and thereby protect both the surface of said board and the instruments and accessories mounted thereon.

Considering the board when positioned, as shown in Fig. 1 and as in normal use, the rear of 35 the same is provided with a pair of posts 3 between which extends a preferably round rod 4. Also secured to said board, adjacent to but spaced well from the right hand side of the same is an upstanding guide bar 5, which is perpendicular 40 to the axis and the rod 4, and against which a sheet of any suitable paper 6 is normally positioned, such sheet being either partly or entirely blank, graduated, or otherwise printed, or ruled, if desired, and being normally held in this position by means of resilient fingers 7 and 8 which are pivotally mounted at 9 and 10, respectively, to the guide bar 5 and directly upon said board 1. 45

Said guide bar is provided with an upward extension 11, which is provided in turn upon one 50 side with a vertically extending slot 12, which slot, at its lower end enters a deeper recess 13. Into this recess normally extends the end portion 14 of a tubular gauge 15, carrying upwardly extending lugs 16 which are spaced apart at regu- 55

lar intervals 17, and preferably beveled at their upward corners 18 for a purpose hereinafter described. These lugs are for convenience secured within an elongated slot 19 in the top of the 5 gauge 15 when in operative horizontal position, the end lug 16a extending into the slot 12 of the bar extension 11 to prevent the gauge bar 15 and the lugs carried thereby from rotating angularly.

The opposite lug 16b for a similar purpose extends into a similar slot 12a in a post 20 carried by the board 1 in widely spaced relation with respect to the guide bar 5 and its extension 11. The vertical surface of the second post 20, facing the extension 11, is also provided with a shallow recess 21, normally extending into which is a ball 22, positioned in the adjacent end of the tubular gauge 15, and thrust yieldingly outward by means of a spring 23 within said member. With this construction said gauge 15 and the lugs carried thereby are normally positioned as shown in Figs. 1, 3, 4 and 5, but may be readily withdrawn in order to replace them with other similar substitute members characterized, however, by lugs of different widths and/or spacing than those herein represented.

The board 1 is, furthermore, provided with a recess in which is secured any well-known form of ink pad 24, normally spanned and protected by a removable cover 25, while there may be also secured to said board a suitable holder 26 for ink, such as is used to re-ink the pad 24.

Among the accessories of such a drafting device is a series of stamp elements, which are preferably composed of rubber, molded in any well-known manner and so molded as to represent any desired indicia whatsoever. In the drawings forming a part of this application, the printing surface of the member shown in Fig. 7, as well as those represented by the consecutive impressions shown in Figs. 12, 13 and 14 are formed to represent units of kitchen equipment, though it is to be understood that the improved drafting device as a whole, and the individual stamp members per se, may instead comprise any indicia necessary to represent or illustrate any one or more of an infinitely wide variety of subjects. For instance, it may be stated that such a series of stamp elements may be used in conjunction with this improved drafting device, in order to represent or illustrate the great number of units which are designed to be assembled selectively, to form an extensive up-to-date modern power-house switch board installation.

Each of the stamp members comprises a yielding body of extremely live rubber or equivalent 55 27, a form of which has been designed for use in the present device, such as is capable of long life and use without becoming distorted, due to shrinkage, warping, or other form of aging or 60 deterioration. The outer active or impression face of this rubber body carried the molded extensions 28 in relief, as in the case of an ordinary rubber stamp, while said body is directly cemented to a plate 29, provided with a notch 30 at one end and with a recess 31 at its opposite end adjacent to and extending into a normally upstanding angular portion 32. As before indicated, there is provided a rather extensive series of these stamp members or units and the same, 65 if desired, may be carried in any suitable manner by the cover hereinbefore referred to, which in turn may be hingedly connected to the board 1, but the exact construction of which is not considered an essential detail of the present invention.

For accurately positioning one of the rubber stamp bodies 27 with respect to its particular plate 29, there is provided a jig, such as is shown in Figs. 8, 9, 10 and 11, comprising a body portion 33 surrounded on three sides by a slightly elevated ridge 34, between and against which a stamp body is positioned, and upon which latter a base plate 29 is then cemented, with the sides of the notch 30 of such plate straddling an upwardly extending guide post 35, forming an integral projection upon one end portion of the jig body 3. The opposite end of said jig body is provided with a recess 36, in which is yieldingly positioned an upwardly extending guide finger 37, operatively positioned by means of a coil spring 38, surrounding an adjustable screw 39 by means of which the tension of said spring upon said finger is varied, as desired. When one of said plates has been thus operatively positioned and fixedly secured to a rubber stamp member in predetermined standardized relation, in order to produce at all times parallel impressions of the respective stamp members, as indicated in Figs. 12 and 13, the composite stamp unit may be removed from the jig and is ready for use in such manner that the impressions made by consecutive stamps overlap only to the extent of the width of their laterally opposite marginal lines, which, therefore, in the final layout accurately coincide, as shown.

A stamp unit holder is shown in Figs. 1, 2, 3 and 5a, and comprises an arm 40 carrying at its rear end a relatively heavy head 41, provided with a transversely extending groove 42 upon its under side, and through which groove normally extends the rod 4, about the axis of which the arm 40 is adapted to be manually oscillated by means of a handle 43, attached to an extension 44 of said arm, which is preferably depressed or offset in a plane beneath and spaced from that of the arm 40, and normally accurately parallel with the plane 45 of the board 1 and consequently that of the sheet of paper or the like 6. The under surface of the arm extension 44 is provided rearwardly with an undercut lug 46, for receiving the notched portion 30 of the plate 29 while said plate lies closely adjacent to and parallel with said arm extension, in which position it is normally operatively secured by means of a latch mechanism 47, carried by the outer free end of said arm extension, and having a downwardly extending projection 47, which normally extends through or at least into the aperture 31 and the plate 29, while the latch mechanism may be released by means of a lever 48 in any well-known manner. The under side of the forward portion of the arm 40, rearwardly of the extension 44, is also provided with a guide post 48 from which extends forwardly a lug 49, which in turn normally enters one of the spaces 17 between adjacent spacing lugs 16 upon the bar 15.

In the operation of this device with a sheet of paper 6, or the like, operatively positioned against the guide bar 5 by means of the resilient fingers 7 and 8, the arm 40 is raised and, if desired, entirely removed from engagement with the rod 4, whereupon any one of a series of stamp units is secured to the arm extension 44, as above described, and the arm replaced upon the rod 4, however, with the face of said stamp unit in contact with the inking pad 24, against which said member is pressed in order to deposit ink upon the raised surfaces 28 of the stamp. Having inked the stamp, the arm 40 is shifted longitudinally upon the arm 4, and thereupon low-

ered angularly downwardly until its lug 49 enters the proper space 17 of the space bar 15, and thereafter until the stamp can be pressed upon the sheet 6, as for instance in the initial position indicated by the broken lines 50.

After being re-inked, a second impression of the same stamp may be made upon the same sheet, but if only one of the units represented by such stamp is desired at this point in the 10 particular layout, the arm 40 is raised from the rod 4 and the stamp detached therefrom, being replaced by a stamp representing another type of unit, after which the arm is replaced upon the guide rod, the second stamp is inked and 15 thereupon impressed upon the sheet 6 adjacent to or spaced from the impression 50, after the notch 49 has been made to enter the proper space 17, either adjacent to the space previously entered, or, in fact, into any other of the several 20 spaces provided for this purpose. After a series of such impressions have been made upon the sheet, such for instance, as the composite elevational layout shown in Fig. 12, the plan of the working surfaces of the units represented 25 by some or all of the units shown in Fig. 12 may be arranged in a separate row, as indicated by Fig. 14, spaced from the above-mentioned plan simply by shifting the sheet 6 forwardly or rearwardly in a direction parallel with that of 30 the guide bar 5.

As hereinbefore mentioned, the stamp units represented are merely illustrative of an infinite variety which may be employed, but which in order to carry out the illustration will be identified insofar as they relate to kitchen equipment. Therefore, the impression 51 comprising Fig. 12 is that of an upwardly positioned 35 closet space having a pair of doors 52, beneath which is represented a working surface of table 40 53, upon the top of a compartment normally closed by means of a door 54. In Fig. 13, the first two impressions 55 are similar and represent upper closets 52 beneath which is provided a continuous working surface 53 above pairs of 45 vertically arranged drawers 56.

The next unit 57 shows one-half of a window 58 above a sink 59, beneath which sink is positioned a tier of drawers 60. The next unit 61 provides the second half of the window 58 50 above a drain board, or like surface 62, above a tier of drawers 60. The next unit is similar to the first two mentioned and is, therefore, correspondingly numbered. The next unit comprises an upper compartment 52 enclosed by doors above 55 a range 63, while the last unit comprises a similar door-enclosed upper compartment 52, above a vertically elongated compartment 64, which provides space adapted for cleaning and similar devices. Since the units represented in Fig. 60 14 correspond with the first six units of Fig. 13, they show the same working surfaces 53, the sink 59, drain board 62, a third working surface 53 and finally that of the range 63, the last unit of Fig. 13 not being shown in plan view 65 as no working surface is provided by it.

Referring to Figs. 15 to 19, we find that between and trunnioned in the supporting posts 3 is a bar 65 of polygonal and preferably rectangular cross section, said bar being provided 70 with spaced recesses 66, the spaces between their centers being equal to the width of the several rubber stamps or dies 27, representing the respective kitchen or other units in elevation, and also the width of the corresponding plan views 75 27a of such units. Slidably upon said bar is a

block 67 having a channel 68 of the same width and general shape as that of the bar which extends thru it. One wall of said block is pierced by an aperture 69 in which is positioned a ball or the like 70, which under the influence of a 55 suitable spring 71 is normally forced yieldingly into any one of said recesses 66 selectively, it being understood that instead of the ball and spring shown any other desired means may be employed, for normally maintaining said block 10 in a given laterally adjusted position.

Secured to and extending forwardly from said block, and in normal parallelism with the surface of the board or base 1, is a metallic arm 72, preferably provided with a handle 73 and upon 15 its free end with a latch 74, equivalent to the latch mechanism 47 hereinbefore described, while the rear end of said arm is provided with an aperture 75, or equivalent means for attachment thereto of the reduced end 76 of a plate 20 77, which in turn carries the rubber stamps or dies 27 and 27a, and at its opposite end is normally secured to said arm by means of the latch mechanism 74. In this form of stamp or die supporting plate, it will be noted that said 25 plate is provided with positioning means such as the recesses 27b and 27c, for the reception of the respective stamp units 27 and 27a, respectively. Such a construction eliminates the need of providing a jig, such as that hereinbefore 30 described, and insures the proper spacing apart of the elevation and plan view stamp units, their simultaneous use and equal impression upon a given sheet of paper or the like, thereby always insuring their proper association in related pairs, 35 and also the proper alignment with each other and their registry and alignment with the impressions of adjacent units.

In reading and considering the above description and the appended claims, it is to be understood that various additional modifications may be made in the details of construction and operation of the device, without departing from the scope of the broad idea of the invention as conceived.

Having thus described my invention, what I claim as new and desire to protect by Letters Patent of the United States is:

1. The method of making a drafting layout, which consists in using a series of stamps representing a given set of assemblable units, impressing one such stamp upon a receiving surface, then impressing the same or other stamps of the series upon such surfaces in sequence and juxtaposition, so that a portion of the second stamp registers with the impression made by the first stamp to represent the cumulative result of the elements which the respective stamps represent.

2. The combination of a base, a guide carried by said base, an arm having a groove adapted to 60 receive said guide, a stamp, means to detachably secure said stamp to said arm, and a gauge fixed with respect to said base and operative to position said stamp in any one of a plurality of predetermined positions for impression upon a sheet 65 positioned upon said base, while said arm is in longitudinal and angularly oscillatable contact with said guide, and said arm, after oscillation out of engagement with said guide, then longitudinal displacement upon said guide, and reverse oscillation upon said guide into re-engagement with said gauge, being operative to so position said stamp as to make a second impression upon the sheet, having a definite relation with respect to said first impression.

3. In a drafting device, the combination of a holder, with a gauge having spaced irregularities, means to normally support the opposite ends of said gauge, and means to yieldingly secure one end of said gauge with respect to said first means.
4. In a drafting device, the combination of a holder comprising a pair of spaced surfaces provided with engageable surfaces, with a gauge having spaced irregularities, one end portion of said gauge being normally in engagement with one of said surfaces, and means to yieldingly secure the opposite end portion of said gauge in normal fixed relation with respect to the other of said surfaces.
5. A drafting device, comprising a base, a transversely extending guide rod carried by and

adapted to oscillate angularly with respect to said base, a block slideable upon said rod, means to yieldingly maintain said block in any one of a plurality of predetermined positions upon said rod, an arm extending laterally from said block, a plate, provided with a plurality of definitely spaced recesses, a plurality of related stamps carried by said plate and permanently associated in predetermined relationship by said recesses, and means to detachably secure said plate to said arm, the relation of the size of said stamps to the spaces between said recesses being such that a portion of one stamp registers with the impression made by another stamp.

HOWARD C. BLINSINGER.

15
